COMBINATION SCIENCE TABLE

Burton T. Collins, Eureka, Utah

Application December 29, 1941, Serial No. 424,836

3 Claims. (Cl. 155—123)

My invention relates to new and useful improvements in combination science tables adapted for use in schoolrooms or other places and the principal object of the invention resides in the provision of a table of the character described including what might be termed a cabinet portion and adjustable or slideable chairs or seats and desks or tables adapted to be normally positioned within recesses or compartments formed in the cabinet portion, but adapted to be moved to positions outside of the cabinet portion for use by the students.

Another object of the invention consists in novel means for mounting the chairs or seats and desks or tables relative to the cabinet portion whereby the chairs or seats and desks or tables may be readily slid into recesses or compartments within the cabinet portion or slid therefrom to positions outside of the cabinet portion, the mountings being of such a character that slideable chairs or seats and desks or tables may be positioned on opposite sides of the cabinet portion and when slid into position within the recesses of the cabinet portion certain parts thereof may overlap thereby providing a relatively compact structure for use in a minimum amount of space.

A further object of the invention resides in the provision of a novel form of mounting for the slideable chairs or seats and desks or tables whereby when they are withdrawn from the cabinet portion they will be held in position against accidental sliding movement or displacement.

With the above and other objects in view, which will appear as the description proceeds, my invention consists in the novel details of construction, and arrangement of parts, described in the following specification and illustrated in the accompanying drawings, and while I have illustrated and described the preferred embodiments of the invention, as they now appear to me, it will be understood that such changes may be made as will fall within the scope of the appended claims.

In the drawings—

Fig. 1 is a top plan showing the slideable seats and desks or tables in extended position relative to the cabinet portion.

Fig. 2 is a front elevation of the cabinet portion with parts positioned as shown in Fig. 1.

Fig. 3 is a side elevation with the slideable seats and desks or tables in position within the recesses or compartments of the cabinet portion.

Fig. 4 is a longitudinal vertical section through the cabinet portion on the line 4—4 of Fig. 3 looking in the direction of the arrows.

Fig. 5 is a longitudinal section through the

cabinet portion on the line 5—5 of Fig. 3 looking in the direction of the arrows.

Fig. 6 is a horizontal section on the line 6—6 of Fig. 4 looking in the direction of the arrows.

Fig. 7 is a fragmental detail showing a portion of one of the slideable seats and one of the mountings therefor.

Fig. 8 is a transverse section on the line 8—8 of Fig. 7.

10 Fig. 9 is a top plan of the construction shown in Fig. 7 with parts shown in horizontal section.

Figs. 10 and 11 are details showing a modified form of my invention in which the back of the seat is adapted for swinging movement into vertical or horizontal position.

15 I am well aware that combination science tables have been in use for some considerable time and such tables have been provided with a stationary desk or desks and chairs have been provided for use by the student or students working on the desk or desks.

With a construction such as this the desks always project from the table, or what might be termed the cabinet portion thereof, and often the chairs or seats, provided 20 for the student, are not of the proper height relative to the desk. With the construction which I provide the seats or chairs are of the proper size or height relative to the height of the desks or tables and when not in use the chairs and desks

25 30 may be positioned within the recesses or compartments in the cabinet portion so that chemicals cannot be spilled on them, when the student is using the top of the cabinet portion as a work table and they will not be in the way of the student or students so working.

The seats or chairs and the desks or tables do not extend above the top of the cabinet portion to interfere with vision when the room is used as a study room and the rod which acts to hold the fume hoods upon the 35 40 cabinet portion may be dropped or lowered relative to the top of the cabinet portion so as not to obstruct the view of the students.

In the drawings, particularly in Figs. 1 and 2 thereof, I have illustrated what might be termed 45 a single unit, each unit including a cabinet portion, two desks or tables, and two seats or chairs.

When desired a plurality of these units may be placed together to provide an elongated science table of the desired length according to the size 50 of the room in which used.

In the drawings A denotes what might be termed the cabinet portion of a combination science table, B and B' indicate slideable desks or tables positioned at opposite sides of the cabinet portion A and C and C' indicate slideable seats or chairs at 55 opposite sides of the cabinet portion and adapted

to be positioned relative to the desks or tables B and B', as shown more particularly in Figs. 1 and 2 of the drawings. In these Figs. 1 and 2 the desks or tables B and B', as well as the slideable seats or chairs C and C' are shown in what might be termed extended position relative to the cabinet portion A, but it will be understood that they are adapted to be slid into recesses or compartments within the cabinet portion A, as shown more particularly in Figs. 3, 4, 5 and 6 of the drawings. The cabinet portion A is provided with a sink a, water faucets b, gas cocks c and vacuum exhaust pipe connections d all of which are of well-known construction for use in connection with science tables and a further detailed description thereof is not thought necessary.

Drawers are slidably mounted in each side of the cabinet A, the drawers 1 and 2 at each side being slideable upon a plate 3 and positioned just beneath the top of the cabinet portion A as shown more particularly in Fig. 3 of the drawings. A drawer 4, at each side of the cabinet, is slideably mounted in a casing or housing 5, drawers 6 and 7 are slideably mounted in a casing or housing 8 and drawers 9, 10 and 11 are slideably mounted in a casing or housing 12. The casings or housings 5 and 12 are suitably supported on the base foundation of the cabinet A and may be secured thereto through the medium of nut and bolt fastenings or, if desired, by a welding process. The outer walls of the casing or housing 5 and casing or housing 8 are spaced from the front wall or face 13 of the cabinet A to provide the vertically extending recess or compartment 14 extending along the side of the drawer 1. The outer wall of the casing or housing 12 is spaced from the rear wall 15 of the cabinet A to provide the vertically extending recess or compartment 16. The inner walls of the casings or housings 5 and 8 are spaced from the inner wall of the casing or housing 12 to provide the vertically extending recess or compartment 17. The bottom of the casing or housing 5 is spaced from the top of the casing or housing 8 to provide the recess or compartment 18 and the bottom of the plate 3 is spaced from the top of the casing or housing 12 to provide the recess or compartment 19. At 20 and 21 I have provided respectively relatively shallow and narrow drawers for desired uses of the students. It will be understood that each side of the cabinet portion A is of the same formation as shown in Fig. 3 and the recesses or compartments at one side will communicate with and form a continuation of the recesses or compartments at the opposite side.

Secured to the inner face of the front wall 13 of the cabinet portion A, and positioned within the recess or compartment 14, are the vertically spaced guides 22 and 23 which extend longitudinally of the cabinet portion. Secured to the inner wall of the drawer casing or housing 12, and positioned within the recess or compartment 17, are the vertically spaced longitudinally extending guides 24 and 25 which are parallel with the guides 22 and 23 respectively, as quite clearly shown in Fig. 3 of the drawings. Secured to the inner face of the rear wall 15, of the cabinet A, and positioned in the recess or compartment 16 in alignment with the recess or compartment 19, are the vertically spaced longitudinally extending guides 26 and 27 which are respectively parallel with the vertically spaced longitudinally extending guides 28 and 29 supported by the brackets 30 and positioned in the recess or compartment 18 in alignment with the recess or compartment 19.

ment 17 in alignment with the recess or compartment 19.

The outer ends of the guides 22 and 24 are formed with a depending notch or recess indicated at 31. As shown more particularly in Figs. 4 and 5 of the drawings the inner ends of the guides 23 and 25 overlap the inner ends of the guides 22 and 24, and the outer ends of the guides 23 and 25 are bent downwardly, as shown, and are provided with the depending recesses 32 corresponding to the recesses 31. By bending the outer ends of these guides 23 and 25 downwardly they will lie on the same plane as the outer ends of the guides 22 and 24 so that when the chairs or seats C and C' are in their extended positions they will be of the same height. The chair or seat C is slideably mounted relative to the cabinet portion A by the guides 23 and 25, whereas the chair or seat C' is slideably mounted relative to the cabinet portion A by the guides 22 and 24. Each of the chairs or seats includes a pair of longitudinally extending horizontal arms 33, a depending leg portion 34 of loop or ring formation, as shown more particularly in Fig. 3 of the drawings, an upwardly extending back 35 and a bottom or seat 35'. The arms 33 are of hollow formation to receive telescoping extensions 36, each of the extensions being provided with a transversely extending bolt or shaft 37, carrying a roller 38, the rollers being adapted to be received in the guides 22, 23, 24 and 25. When the chairs or seats are in their extended positions for use the depending leg portions 34 will rest on the floor or ground and the rollers 38, operating in the guides 22 and 24, will be received in the outer depending recesses 31 of the guides 22 and 24, while the rollers 38, operating in the guides 23 and 25, will be received in the depending recesses 32 of the guides 23 and 25. As has been previously stated the curving of the outer ends of the guides 23 and 25 permit the chair or seat C to assume a position on a level with the chair or seat C'. When the chairs or seats are not to be used they are slid relative to the cabinet portion A to assume the positions shown more particularly in Figs. 3 and 4 of the drawings. When in these positions the backs 35 and one longitudinally extending arm 33, of each chair or seat, will be received within the recess or compartment 14, while the opposite longitudinally extending arm of each chair or seat will be received in the recess or compartment 17. The depending legs 34, of loop formation, will surround the casing or housing 8 with the upper horizontal portion and the seat or bottom 35' received in the recess or compartment 18, one vertical portion will be received in the recess or compartment 14, and the opposite vertical portion received in the compartment or recess 17. The lower horizontal portion of the chair or seat C' will be received in the recess 39 below the casing or housing 8, while the lower horizontal portion of the chair or seat C will be received within the recess 40. The tables or desks B and B' are slideably mounted relative to the cabinet portion A so that they may be extended to the positions shown in Fig. 1, for use, or they may be confined within the cabinet portion. Each of the tables or desks includes the horizontally extending arms 41, supporting a top plate 42, these top plates being of a width as to overlie the bottom or seat portions of the chairs C and C', when extended, as illustrated more particularly in Fig. 1 of the drawings. At their outer ends the arms 41 are bent downwardly to provide the vertically ex-

tending portions 43 connected at their lower ends by the cross bar 44. Adjacent their inner ends the arms 41, of the table or desk B, are provided with the rollers 45 operable in the guides 27 and 29. Adjacent their inner ends the arms 41, of the desk or table B', are provided with the rollers 46 operable in the guides 26 and 28. The inner ends of the guides 28 and 29 overlap, as shown more particularly in Fig. 5 of the drawings, and the inner ends of the guides 26 and 27 are similarly overlapped. At their outer ends each of the guides 26 and 28 is formed with a depression 47, forming a recess for a purpose which will be later brought out, and adjacent their outer ends the guides 27 and 29 are curved downwardly as shown at 48 and terminate in a depressed portion forming a recess 49 on a level with the recesses 47 formed in the guides 26 and 28. When the tables or desks B and B' are in their extended positions, shown more particularly in Figs. 1 and 2 of the drawings, the rollers 46, on the arms 41 of the table or desk B', will be received in the depressed recesses 47 of the guides 26 and 28, while the rollers 45 on the arms of the table or desk B will be received in the depressed recesses 49 of the guides 27 and 29. By curving the guides 27 and 29 downwardly, at their outer ends, when the tables or desks are extended for use, the desk B will be on a level or at the same height as the table or desk B'. When the tables or desks are not to be used they may be slid inwardly relative to the cabinet portion A, the rollers 45 and 46 moving in their respective guides. When slid inwardly into the cabinet portion the table or desk tops 42 will be received in the recess or compartment 19 as will also be the case with the horizontal arms 41. The inner vertical portions 43, of the tables or desks, will be received within the recess or compartment 17, whereas the outer vertical portions 43 will be received within the recess or compartment 16. The cross bar 44, of the table or desk B', will be received in the recess 39, as shown more particularly in Figs. 3 and 4 of the drawings, whereas the cross bar 44, of the table or desk B, will be received in the recess 40, as shown quite clearly in Figs. 4 and 5 of the drawings.

In Figs. 10 and 11 of the drawings I have illustrated a slightly modified form of chair or seat construction in which the backs 35 are hingedly connected to the outer horizontal arms 33 positioned in the recess or compartment 14. For this purpose a casting 50 is mounted on each of the outer arms 33 and has an inwardly directed lug or projection 51 to which a back 35 is pivotally connected at 52. The top or seat portion of a chair or seat is illustrated at 53 and corresponds to the tops or seat portions 35' previously described. With this modified form of the invention, when desired, the backs 35 may be swung downwardly over the seat or top portions 53 and when the chair or seats are positioned within the cabinet portion A will be received within the compartment or recess 18.

From the above detailed description it is thought that the construction and advantages of my improved form of science table will be appreciated and it will be seen that I have provided a novel construction wherein the tables or desks and chairs or seats used by the students may be positioned within the cabinet portion when not in use and tests may be made on the cabinet portion without the fear of spilling chemicals on the work desks or students' chairs or seats. At the same time I have provided a construction

wherein the desks or tables and chairs or seats will be of the proper height for use by the students and in connecting the desks or tables and the chairs or seats to the cabinet portion for sliding movement relative thereto there is no chance of displacing the tables or desks and chairs or seats and they will always be in proper position for use by the students or to be slid into the confines of the cabinet portion. As I have stated in the objects of my invention, I am well aware that tables or desks and seats or chairs have been provided for the use of students in connection with science tables in the school rooms, but so far as I am aware, it is new with me to provide a table of the character described in which the students' desks or tables, as well as the chairs or seats are connected to the cabinet portion and are adapted for sliding movement relative thereto. When in the extended positions, shown more particularly in Figs. 1 and 2 of the drawings, the chairs or seats are properly positioned with respect to the tables or desks and when it is desired to discontinue use of the chairs or seats and desks or tables they may be slid towards and into the cabinet portion. For the sliding of the tables or desks and chairs or seats I have provided guides of novel formation and have positioned them so that the minimum amount of space may be used. In the modified form of chair or seat illustrated in Figs. 10 and 11 of the drawings, I have provided a chair or seat with a folding back and this may be advantageous in some instances.

Having fully described my invention what I claim as new and desire to secure by Letters Patent is:

1. A science table including a cabinet portion having receiving passages for a desk and chair opening to each side of the cabinet portion, a desk and chair at each side of the cabinet portion, and means slidably connecting the desks and chairs with the cabinet portion, said means providing for vertical movement of one of the desks and chairs relative to the other desk and chair the respective supporting portions of the desks and chairs when extended being at the same level, said desks and chairs being nested when moved into the cabinet portion.

2. A science table including a cabinet portion having passages at opposite sides thereof to accommodate cooperatively associated desks and chairs, means slidably connecting a chair and desk at each end of the cabinet portion, the slideable connections being in overlapping relationship interiorly of the cabinet portion, said slideable means including means for leveling the supporting portions of the opposite chairs and desks when the tables and desks are withdrawn from the cabinet.

3. A science table including a cabinet portion open at opposite sides for the reception of cooperating desks and chairs, means slidably connecting each desk and chair interiorly of the cabinet portion whereby each chair and desk may be withdrawn from the cabinet in a direction opposite to the withdrawal of the other desk and chair, the slideable connecting means for the opposite desks and chairs overlapping interiorly of the cabinet, the upper overlapping portion of the slideable means being formed at the end with a downward portion whereby the legs of the chair and table guided thereby will be lowered to the supporting level of the legs of the table and chair guided by the under slideable means portion.

BURTON T. COLLINS.
